INPUT-OUTPUT UNIT FOR A DATA PROCESSOR

Collan B. Kneale and Frank Wilkey, Jr., Rochester, Minn.,
assignors to International Business Machines Corpora-
tion, Armonk, N.Y.

Filed Jan. 26, 1973, Ser. No. 326,638

Term of patent 14 years

Int. Cl. D14—02

U.S. Cl. D26—5 C

FIG. 1

FIG. 2

FIG. 1 is a front perspective view of an input-output unit for a data processor, showing a first form of our new design; and

FIG. 2 is a front perspective view of an input-output unit for a data processor, showing a second form of our new design.

The rear and left side covers of the units shown in FIGS. 1 and 2 are duplicates of the front and right side covers of FIGS. 1 and 2, respectively, except that the left side covers are blank for both units.

We claim:

The ornamental design for input-output unit for a data processor, as shown and described.
